UNITED STATES PATENT OFFICE

2,452,250

BRAIDING MACHINE CARRIER

Albert T. Lochner, Louisville, Ky.

Application February 9, 1948, Serial No. 7,137

15 Claims. (Cl. 87—56)

This invention relates to a braiding machine carrier, such as is employed in the manufacture of shoe laces, covering wire, or the like, where a plurality of strands of wire, thread or yarn are intertwined or interlaced together to form the finished product.

An object of this invention is to maintain an even constant unwinding of the strands of yarn or wire, or other suitable material, from a bobbin, so that the strands, each being unwound from a separate bobbin, may be intertwined or interlaced with the proper and needed amount of tension imposed on each strand.

Another object of this invention is to unwind the strand from the bobbin, in accordance with the slack or tightness of the strand tension loop at the braiding machine.

Another object of this invention is to unwind the strand from the bobbin without causing the bobbin to rotate or turn, so that a rigid bobbin is employed.

Another object of this invention is to maintain a uniform tension on each strand so that the strands are carried to the braiding machine in proper relation to the other strands, so that a tight and firm braid is obtained.

Another object of this invention is to tension the strand being unwound from the bobbin in response to the pulling force of the strand at the braiding machine.

Another object of this invention is to lock the strand at the point of unwinding adjacent to the bobbin so that the strand cannot be unwound from the bobbin, if there is any slack in the tension loop or at the braiding machine.

Another object of this invention is to provide means, responsive to the pulling force of the strand, to release the locking means for the strand and to thereby allow the strand to be unwound from the bobbin.

With these and ancillary objects in view, this invention comprises certain novel features and arrangement of parts, as will be more apparent in the following description and the accompanying drawings, wherein:

Figure 1 is a side elevational view of a bobbin carrier, constructed in accordance with this invention;

Figure 2 is a rear elevational view of the strand braiding machine carrier, shown in Figure 1;

Figure 3 is an enlarged fragmentary detailed view of means provided to release the clamping or locking means, responsive to the pulling force of the strand or the lack of material in the tension loop.

Figure 4 is an enlarged fragmentary side view of the instant invention exemplifying the guide member, in position to release the clamping means, being moved into said position by the pulling force of the strand;

Figure 5 is an elevational view of Figure 1;

Figure 6 is a vertical sectional view, taken substantially on the line 6—6 of Figure 7, and

Figure 7 is a cross-sectional view, taken substantially on the line 7—7 of Figure 3.

This invention relates to a braiding machine carrier which is employed in association with a braiding machine, each carrier providing an assembly for a bobbin or spool, around which is wrapped the material to be braided, either yarn, wire, or any other suitable strand material. The strand is unwound from the bobbin, under a constant tension, imposed by a locking device and a releasing mechanism, both of which are coactively responsive to the slack or pulling force present on the strand adjacent to the braid former of the braiding machine.

It is necessary in employing a plurality of bobbins, dependent upon the number of strands desired to be intertwined or interlaced, that each strand is received at the braid former under the same tension, so that the braid is formed firm and constant.

Many tensioning devices have been provided to retain the strand under constant tension from the unwinding operation to the formation of the braid. This invention seeks to facilitate the formation of a braid by maintaining each strand of the braid under a separate tension, responsive

to the state of the strand at the braid former, so that each strand will be unwound from the bobbin, in accordance with the amount of strand needed by the braid former to form the braid. The strand as it is unwound from the bobbin, which

is rigid on the spindle, is guided through a locking sheave or pulley, which is normally locked, so that the strand cannot be unwound from the bobbin. However, when the slack is taken up by the braid former and more strand is needed, a

pulling force is exerted by the strand and causes release means to move into operative engagement with the clamping means and thereby releases the clamping means, to allow the desired amount of strand to be unwound from the bobbin. When

such amount has been unwound, a slack in the strand is present and the releasing means is moved out of engagement with the clamping members, so that the strand is again locked or clamped in the locking sheave.

In carrying out this invention, generally de-

noted by the character reference 10, there is provided a base 12, of any suitable material and of any desired shape or size. Formed integrally with the base and extending therebelow, is an attaching post 14, by means of which the carrier 10 is secured to a support.

Secured to the top of the base or support 12 is a bottom or base 16, which also serves to support the guide and tensioning assembly for the strands.

Firmly supported in the bottom or formed integrally therewith is a spindle, 17, which comprises a tube, of any desired length or circumference and of a desirable material, such as metal or wood. Supported on the base 16 by means of the spindle is a spool or bobbin 18 having its bottom disk supported flush on the top surface of the assembly support or base 16.

Wound around the bobbin or spool is a continuous strand 20 of any suitable material, such as wire or thread or yarn, which is to be unwound from the bobbin by means of the braid former on the braiding or quilling machine.

The support post and the bobbin are formed so that the carrier may be employed in a vertical, horizontal or angular position relative to a braid former. The bobbin or spool 18 has its material holding hub formed of a diameter approximating the diameter of the spindle, so that the bobbin is held securely on the spindle and rotation or turning of the bobbin on the spindle is prevented.

Thus it can be seen that the bobbin is rigid on the support and the strand is uncoiled or unwound from the bobbin by moving up and around the top of the bobbin from the uppermost part of the bobbin, gradually unwinding toward the bottom.

Suitable means are provided to maintain a constant and even tension on the strand and comprises a tensioning mechanism and guide structure.

The guide means and tensioning means 22 comprises a pair of spaced support rods, 24 and 26, which extend from the support to a point beyond the top of the bobbin and are maintained in spaced relation at their extending points by means of a cap member 28. This cap member 28 comprises a rectangular bar, having a bore, countersunk at each end thereof, to receive therein the extending points of the rods. Conventional means are employed to maintain the rods in the bores of the cap member and may include soldering as at 30.

Secured to one side of the cap member and extending at right angles, in working operation, from the longitudinal plane of the support rods is a bracket arm 32 which is secured to the cap member by any suitable means such as screw 34, which is inserted through an aperture in the bracket arm and is received within the side of the cap or head member 28.

The bracket arm 32 is angularly bent, so that the terminating portion, which is formed in the shape of a round disk or plate 36, extends outwardly in line with the space between the two support rods 26 and 24.

Secured to one side of the disk-shaped portion 36 of the bracket arm is a locking sheave or pulley 38, which comprises a pair of cooperating disks 42 and 44, which are secured to the bracket arm, by means of a transverse pin or bolt 46, which extends through suitable apertures centrally disposed in the cooperating disk and the bracket extension. Suitable means are provided to secure the connection and includes a nut 48

threaded on the extending end of the pin or bolt 46, which extends through the disk-shaped extension 36 of the bracket arm 32.

Suitable means are provided to urge the disks together, so as to form the locking pulley 38, which is employed for controlling the unwinding of the strand, and comprises a sleeve or bushing 50 which is received around the pin or bolt, and also serves to space the nut 48 from the head of the bolt 46. A spring 52 is supported at one end by the head of the bolt 46 and enlarges or flares outwardly around the sleeve 50, having its other end of a larger diameter and securely abutting or pressing against the side of the disk 44, so that the disk 44 is urged or moved into clamping engagement with the disk 42. The strand of material 20 inserted between the two cooperating disks 42 and 44 is thereby clamped between and is prevented from winding off the bobbin or spool 18.

Of course, the bracket arm, supporting the locking sheave assembly, is swivelly secured to the cap or head member 28 by means of the screw 34, so that the entire assembly may be moved from its normally horizontal operative position at right angles to the support rods, to a point in longitudinal alignment with the support rods. This swivel construction is provided in order that a new spool or bobbin may be inserted on the spindle 16 by merely unscrewing the screw 34 and moving the bracket arm, so that the bobbin may be pulled off and a new one may be inserted on the spindle.

A guide sleeve 54 is formed integrally with the cap head and extends outwardly therefrom at the opposite side of the bracket arm and is employed to guide the strand 20 so that the strand is brought from the carrier to the braiding machine in a straight line as shown in Figure 1 of the drawings.

Suitable means are provided, responsive to the pulling force of the strand at the braiding machine, to engage and release the locking sheave 38. This means comprises a guide rod 56, having one end freely inserted in or mounted in the support 14, and the other end received within a sleeve 58 formed in the cap or head member 28. This guide rod is of a smaller diameter than the support rods and extends longitudinally therewith being positioned and spaced between the support rods.

Received on the support rods and guide rod for reciprocating movement thereon is a guide member 60, having arcuate downwardly depending arms 62 and 64 formed on each side thereof and which extend freely around the support rods. Sleeves 66 are formed integrally with the guide member 60 and serve to position the member for movement on the rods. A hook 68 is inserted in the top surface of the guide member 60 and is adapted to receive a strand 20 of the material. Coil springs 70 and 72 are formed around the surface of the support rods and are employed to maintain the guide member 60 in close proximity with the support 16.

Formed on the guide rod 56, are a pair of plates or washers 73 and 74 which form a groove on the guide rod, about which is positioned the extending closing arms 76 and 78 of a bifurcated lever 80. Lever 80 is pivoted to the outer surface of the disk-shaped extension 36 of the bracket arm by means of the pivot pin 82. The opposite end of the bifurcated lever is arcuate in shape and corresponds to the round contour of the disk extension 36. An offset portion 83 is formed on

one side of the arcuate end of the lever 80 and wedge-shaped extensions 84 and 86 are formed on the offset portion 83. The wedge-shaped extensions 84 and 86 are adapted to engage the cooperating disks 42 and 44 and to move therebetween spreading or forcing the disks apart and allowing the strand of material to be pulled through the locking sheave 38.

It can thus be seen that by moving the actuating or guide rod 56 upwardly, the arms 76 and 78 of the bifurcated lever, which are formed around the groove on the actuating rod, will be limited in their movement by the plates 72 and 74 and will be moved with the actuating rod thereby. Thus the rod moving upwardly would cause the bifurcated lever 80 to pivot around the point 82 and would move the offset portion 83 and the appurtenant wedges 84 and 86 into a spreading engagement between the cooperating disks 42 and 44.

Suitable means are provided to move the actuating or guide rod 56 upwardly and include a plate or washer 88 which is formed securely on the actuating rod 56 and which limits the upward movement of the guide member 60, as the sleeve of the guide member moving on the actuating rod would contact the plate or washer 88 and would move the actuating rod upwardly thereby. The actuating rod, of course, is loosely inserted or mounted in an axial bore formed in the support plate 14.

In operation, the material is already wound around the bobbin or spool 18. The spool 18 is then inserted on the spindle 16 by first raising the bracket arm 32 from the position extending over the spindle. One end of the strand 20 is then inserted between the cooperating disks by manually spreading the disks apart and is threaded around the sleeve 50. The strand is then brought downwardly behind the bobbin or spool and is inserted around the hook 68 and then through the guide sleeve 54 and horizontally to the braiding former on the braiding machine.

The braiding machine is then rendered operative and the braid former begins its operation whereby the strand of material being tight from the carrier to the braiding machine will cause the guide member 60 to move upwardly on the support rods 24 and 26, against the pressure of the springs 70 and 72 coiled around the operating rods. When the sleeve of the guide member 60 which is received around the actuating or guide rod 56 contacts the outer surface of the plate or washer 88 thereon, the actuating rod is moved upwardly. As the rod moves upwardly, the arms 76 and 78 of the bifurcated lever are moved upwardly accordingly, by means of the plates 72 and 74 formed on the actuating rod. The lever 80 is then pivoted on the point 82 and the wedge portions 84 and 86 are moved in between the cooperating disks 42 and 44. The wedge portions move or spread apart the disks, as shown in Figure 7 of the drawings, and the strand is free to move therebetween. The strand of material is then unwound from the rigid bobbin until a desired amount of slack is obtained, whereupon the springs 70 and 72 will force the guide members 60 down to an inoperative position, as shown in Figures 1 and 2 of the drawings. This will allow the actuating rod 56 to move downwardly within the sleeve or bore formed in the support 14 and the wedge portions 84 and 86 of the bifurcated lever 80 will accordingly drop away from engagement with the inner surfaces of the cooperating disks 42 and 44 and the spring 52 will move the

disk 44 to clamping engagement with the disk 42. Thereby, the strand of material 20 will be held securely in the locking sheave 38.

From the foregoing, it is thought that the construction and operation of the device will be readily understood. Obviously, the dimensions of the carrier and the supporting structure therefor, may be such that a smaller or larger bobbin or spool may be readily and easily employed and that the spring employed on the support rods 24 and 26 may be of sufficient tension, dependent upon the strength or size of the strand of material.

It will thus be seen that there has been provided a device which with ease and accuracy will facilitate the unwinding of material from a bobbin or spool for a braiding or quilling machine and also be used for any other type of textile machine, which will employ or which would need a carrier device, to facilitate the unwinding of material from a spool or bobbin.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the invention as herein described and the scope of the appended claims.

Having described the invention, what is claimed as new is:

1. A braiding machine carrier comprising a support, a spindle mounted on said support, a wound bobbin carried rigidly by said spindle, a pair of support rods secured to said support, a bracket swivelly secured to said support rods, a pair of cooperating guide disks for the strand unwound from the bobbin carried by the bracket, resilient means for normally retaining said disks in a clamping relation to lock the strand therebetween, an actuating rod carried by said support and disposed parallel with the support rods, a guide member slidably mounted on said support rods and operatively associated with the actuating rod, said guide member being moved on the rods responsive to a pulling force exerted by the strand, means on said actuating rod for moving the same upon engagement thereof by the guide member, an annular groove formed in said actuating rod, a release member for said disks pivoted to said bracket and having one end received in said groove, resilient means on said support rods for normally retaining said guide member in a seated placement on the support.

2. A braiding machine carrier comprising a support, a spindle mounted on said support, a wound bobbin carried rigidly by said spindle, a pair of vertical support rods mounted on said support, a connecting member received on the extending ends of the rods, a guide secured to said member, a bracket swivelly carried by said connecting member, a pair of cooperating guide disks for the strand unwound from the bobbin carried by the bracket, resilient means for normally retaining said disks in a clamping relation to lock the strand therebetween, an actuating rod carried by said support and disposed between the support rods, a guide member slidably disposed on said support rods and operatively associated with said actuating rod, said guide member being moved upwardly on the rods re-

sponsive to a pulling force exerted by the strand, a stop member on said actuating rod for limiting upward movement of the guide member thereon and thereby raising the actuating rod corresponding to movement of the guide member, an annular groove on said actuating rod, a release member for said disks operatively associated with said groove and pivoted to said bracket and resilient means disposed on said support rods between said connecting member and the guide member for normally retaining said guide member in a seated position on the support.

3. The combination of claim 2, wherein said release member includes a lever having an arcuate end pivotally mounted on the bracket, a pair of wedge extensions carried by said arcuate end in alignment with the cooperating disks, said lever terminating in a pair of branches disposed in the annular groove in the actuating rod.

4. A braiding machine carrier comprising a support, a spindle mounted on the support, a bobbin rigidly held on said spindle, rods secured to the support, an actuating rod carried by the support, a bracket swivelly associated with said rods, a pin transversely journalled in said bracket, a pair of opposed disks received on said pin and forming a sheave to accommodate the strand, resilient means for urging said disks into clamping engagement, means carried by said actuating rod and associated with said bracket for selectively engaging and releasing the disks from clamping engagement in response to a pulling force exerted by the strand.

5. A braiding machine carrier comprising a support for a wound bobbin, guide means for the strand unwound from the bobbin, braking means for retaining said guide means in a clamping relation with the strand, means operatively associated with said braking means for selectively engaging and releasing the braking means, said last mentioned means including an actuating rod, said releasing means being operatively associated with the actuating rod and means for moving said actuating rod responsive to the pulling force of the strand.

6. A braiding machine carrier comprising a support for a wound bobbin, rods secured to the support, a bracket adjustably extending from said rods, a pin transversely journalled in said bracket, a pair of opposed disks received on said bracket, a pair of opposed disks received on said pin and forming a guide sheave to accommodate the strand from the bobbin, resilient means for urging said disks into clamping engagement, means responsive to the pulling force of the strand, for selectively engaging and releasing the disks from clamping engagement, wherein the resilient means includes a spring secured on the pin and engaging one of the disks.

7. A braiding machine carrier comprising a support for a wound bobbin, a pair of support rods secured to the support, an actuating rod carried by the support, braking means for preventing the unwinding of the strand swivelly secured to said rods, a guide member for the strand carried by said rods, means for selectively engaging and releasing the braking means actuated by said guide member and actuating rod responsive to the pulling force of the strand.

8. A braiding machine carrier comprising a support for a wound bobbin, rods secured to the support and extending therefrom, an actuating rod carried by the support and extending between the rods, a bracket arm swivelly secured to the rods, a pair of cooperating disks supported by the bracket arm, resilient means for urging

the disks in clamping engagement to prevent the unwinding of the strand guided therethrough, a guide member slidably mounted on said rods, means associated with the bracket arm and actuated by the guide member for engaging and unclamping the disks, said guide member being moved on said rods responsive to the pulling force of the strand.

9. A braiding machine carrier comprising a support for a wound bobbin, rods secured to the support and extending therefrom, an actuating rod carried by the support and extending between the rods, a bracket arm swivelly secured to the rods, a pair of cooperating guide disks for the strand from the bobbin supported by the bracket arm, resilient means for urging the disks into clamping engagement to prevent the unwinding of the strand, a guide member carried by said rods, means associated with the bracket arm and actuated by the guide member for engaging and unclamping the disks, said guide member being moved on said rods responsive to the pulling force of the strand, said unclamping means including a bifurcated lever pivotally mounted to the bracket arm and having an offset wedge portion for moving apart the cooperating disks.

10. A braiding machine carrier comprising a support for a wound bobbin, support rods secured to the support and extending therefrom, an actuating rod carried by the support and extending between the rods, a bracket arm swivelly secured to the support rods, a pair of cooperating guide disks for the strand from the bobbin supported by the bracket arm, resilient means for urging the disks in clamping engagement to prevent the unwinding of the strand, a guide member carried by said rods, means associated with the bracket arm and actuated by the guide member for engaging and unclamping the disks, said guide member being moved on said rods responsive to the pulling force of the strand, said unclamping means including a bifurcated lever pivotally mounted to the bracket arm and having an offset wedge portion for moving apart the cooperating disks, said lever having its extending arms formed about the actuating rod, a pair of plates secured on said rod to receive the arms therebetween.

11. The combination of claim 10, said guide member having offset arm portions, sleeves formed on the inner surface and received on the support rods and actuating rod and a stop plate formed on said actuating rod for raising said rod upon engagement thereof by one of the sleeves of the guide member.

12. A braiding machine carrier comprising a support for a wound bobbin, a pair of support rods secured to the support, an actuating rod carried by the support, braking means for preventing the unwinding of the strand from the bobbin swivelly secured to said support rods, a guide member for the strand carried by said rods, means for selectively engaging and releasing the braking means actuated by said guide member and actuating rod responsive to the pulling force of the strand, said means including sleeves formed on said guide member to secure the guide member on the rods, a plate formed on the actuating rod to limit the movement of the guide member thereon, a pair of plates formed on said actuating rod, a bifurcated lever associated at one end with said plates, an offset wedge portion formed on said lever, whereby when a pulling force is exerted on the strand the actuating rod is moved upwardly

moving the wedge portion of the lever into engagement with the braking means.

13. The combination of claim 12, and resilient means carried by said rods and abutting against the guide member for retaining the same out of engagement with the actuating rod plate, said means being responsive to the tension of the strand.

14. The combination of claim 12, and means for joining said rods and actuating rod at their opposite ends.

15. The combination of claim 14, guide means carried by said joining means.

ALBERT T. LOCHNER.
